UNITED STATES PATENT OFFICE.

LUCIEN BOECHAT, OF RITTMAN, OHIO.

MANICURING TOOL.

Application filed October 18, 1922. Serial No. 595,223.

To all whom it may concern:

Be it known that I, LUCIEN BOECHAT, a citizen of the United States, residing at Rittman, in the county of Wayne and 5 State of Ohio, have invented a new and useful Manicuring Tool, of which the following is a specification.

My invention relates to improvements in manicuring tools; and its principal object 10 is to provide a simple and efficient tool for a manicure, to hold an emery coated sheet or card ready for use, to simplify and improve the manicuring art.

It consists of an article of manufacture, 15 comprising a suitable handle adapted to removably hold an abrasively coated sheet or card, somewhat resembling a blade, for manicuring purposes, as hereinafter fully set forth and as stated in the appended claim.

20 My invention is illustrated by the accompanying drawings, in which similar letters and figures of reference indicate like parts.

Referring thereto, Fig. 1 is a general view of a manicuring tool embodying my invention; Fig. 2 is a longitudinal sectional view of the same on the dotted line 2—2 of Fig. 1. Fig. 3 is a like view showing the card holding member drawn out of the handle in position to admit the card thereto; 25 and Fig. 4 is a plan view of an abrasive card, such as I preferably use for the purpose.

In the drawings, A is the handle, B the abrasive card, which is preferably surfaced 35 with a coating of fine emery, or the like, on both sides and edges, and is of suitable dimensions to lie flatwise snugly between the engaging arms *a* and *b* of the card-holder C. D is a metallic thimble having a conical 40 opening at its outer end, and fitted into the end of the handle A, which is hollowed longitudinally, as at *d*, for the purpose, and to admit the upper end of the card holder C to reciprocate therein and thru said thimble. 45 The card holder C is formed by doubling together lengthwise a strip of resilient metal at its lower end *f*, and spaced apart sufficiently to admit the card B flatwise between its adjacent members *a* and *b* loosely. 50 Said members are secured closely together at their upper ends, and there terminate with a cap *e* which serves to limit their outward movement by abutting against the upper end of the thimble D, as shown at 55 C², Fig. 3, when the card holder is drawn out of the handle a limited distance. Said

members are cut apart at a point slightly within the lower edge of the conical opening of the thimble D when the card holder is drawn out to its limits, as shown in Fig. 3 60 and by their resilience are there spread apart to the limit of said conical opening, as shown at *a*, *b*, whereby said card may be readily withdrawn or inserted, as may be required. When the card is inserted between 65 said members, the latter are tightly drawn together thereon by pushing the card holder upwardly into the cavity *d* within the handle to its limits, by the pressure of said conical surface upon the resilient member *a*, as it slides upwardly into the bore of said thimble, to the position shown in Fig. 2, C', whereby said card B is firmly held in proper position with relation to the handle A, as shown in Figs. 1 and 2. It is 70 also apparent that, by the means aforesaid, abrasive sheets or cards of any desired shape or size for the purpose may be quickly and safely adjusted to the handle, or removed therefrom when change is required on account of use or wear, and a simple and efficient and handy manicuring tool is provided. 75

I do not wish to limit my claim of invention to mere matter of form, but claim such 80 modifications as are fairly within the scope of the invention.

Having thus fully described my invention, what I claim is—

In a device of the character described, the 90 combination with a handle, having a longitudinal cavity therein, an inwardly sloped thimble mounted in the lower end of said cavity, and bored longitudinally a limited distance, a card holder comprising a pair 95 of opposite arms longitudinally disposed and adapted to reciprocate in said thimble a limited distance by manual pressure, said arms cut apart and adapted to spread apart automatically by their resilience when drawn 100 downwardly thru said thimble to predetermined limits, and to be drawn together when pushed upwardly a limited distance thru said thimble, and an abrasively coated sheet or card fitted to lie flatwise between said 105 arms, removably, substantially as set forth.

In witness whereof I hereunto set my hand this 12th day of October, A. D. 1922.

LUCIEN BOECHAT.

In presence of two witnesses:

W. M. SHACKLEFORD,
FRED SHREIBER,
